UNITED STATES PATENT OFFICE

95,500

DESIGN FOR AN OIL BURNING APPARATUS OR SIMILAR ARTICLE

Jackson G. Gilmore and Harold B. Donley, Co-
lumbus, Ohio, assignors to Franklin Oil Heating
Inc., Columbus, Ohio, a corporation of Ohio

Application September 19, 1934, Serial No. 53,332

Term of patent 7 years

To all whom it may concern:

Be it known that we, Jackson G. Gilmore and Harold B. Donley, citizens of the United States, residing at Columbus, in the county of Franklin and State of Ohio, have invented a new, original, and ornamental Design for Oil Burning Apparatus or Similar Article, of which the following is a specification, reference being had to the accompanying drawing, forming a part thereof.

Fig. 1 is a perspective view of the oil burning

apparatus or similar article showing my new design;

Fig. 2 is a top plan view thereof;

Fig. 3 is a side elevational view thereof.

We claim:

The ornamental design for an oil burning apparatus or similar article, as shown.

JACKSON G. GILMORE.
HAROLD B. DONLEY.
